GARMENT BAG MAGAZINE DISPENSER
WITH GARMENT SUPPORT SUSPENDED
UNDERNEATH

Arthur C. Johnston, Minneapolis, Minn.

Original application December 4, 1944, Serial No.
566,626. Divided and this application December 4, 1947, Serial No. 789,687

3 Claims. (CL. 226—18)

1

My invention relates to a novel method of and apparatus for the bagging of garments and is in the nature of a division of my copending application S. N. 566,626, which will mature into Patent No. 2,432,524 of date December 16, 1947 and which is entitled "Accordion folded paper garment bag."

As pointed out in my said above-identified application, the novel bag therein disclosed and claimed is capable of being utilized without any particular dispensing apparatus. However, one of the primary objects of my present invention is to provide a novel apparatus to facilitate the use of the bags therein claimed.

Another important object of my invention is the provision of a novel method of bagging garments for shipment or storage after they have been cleaned and/or pressed.

Another object of my invention is the provision of novel apparatus for dispensing bags of the type disclosed in said above-identified copending application, which is inexpensive to manufacture, easy to install, easy to operate, and durable in use.

The above and still further objects of my invention will become apparent from the following detailed specification, appended claims, and attached drawings.

Referring to the drawings, wherein like characters indicate like parts throughout the several views:

Fig. 1 is a view partly in front elevation, partly in central vertical section;

Fig. 2 is a view partly in side elevation and partly in central vertical section;

Fig. 3 is a partial vertical section taken on line 3—3 of Fig. 1;

Fig. 4 is a perspective view of a folded bag;

Fig. 5 is a vertical section taken on line 5—5 of Fig. 4 as indicated by the arrows;

Fig. 6 is a vertical section taken on line 6—6 of Fig. 4 as indicated by the arrows; and

Fig. 7 is a perspective view of a hanger supporting member used.

Referring with greater particularity to the drawings, a container is indicated, in its entirety, by the numeral 10. While this container may be variously formed, in the embodiment of the invention illustrated, it is shown of generally rectangular form in plan or horizontal cross section. The container 10 may be open at its top and, as shown, is provided with a lid 10a. The longer sides of the container 10 are formed at their bottom edges to provide inwardly-projecting flanges 10b, and the bottom of the container 10

is open between the inner edges of said flanges. At its ends, the container 10 is provided with slots 10c having open lower ends and being disposed centrally of the ends of said container. An elongated slot 10d is provided in the lid 10a and extends longitudinally of the container 10. The container 10 may be supported at a convenient height in any suitable manner, but, preferably and as shown, I provide a board or plate 11 secured thereto to which is secured a laterally-extending supporting member 12. Member 12 can be a part of a bracket attached to the wall or supported from the floor.

The container 10 is adapted to receive a plurality of bags 13 which, as shown, are in comparatively flat folded condition. While said bags could be folded in various ways to be in a readily longitudinally expandable or extensible condition, they are illustrated as formed with transverse accordion-like folds 13a at their opposed sides which extend around the girth of the bags 13. The open ends of the bags 13 are directed downwardly and are thus at the lower side of the bags. Said bags 13 are shown as having elongated slots 13b through their closed ends, and, as shown, are of generally rectangular form with the sides thereof parallel to the edges of the bag bottom. It will be observed that the opposed inner edges of the accordion-like folds 13a are spaced apart, as shown in Figs. 5 and 6, so as to provide an axially-extending passage 13c immediately underlying and in alignment with the rectangular slot 13b in the closed end of the bag.

A member or bar 14 is provided support by the container 10, and while it could be supported in various ways in the embodiment of the invention illustrated, it is shown as having members 14a extending perpendicular to its sides, which members have downturned ends 14b adapted to fit over the sides of the cover 10a. The bar 14 is rectangular in transverse cross section, and the members 14a and 14b are at right angles to each other. The bar 14 extends downwardly through the slot 10d in cover 10a and passage 13c and from thence downwardly some distance below the bottom flanges 10b. It will be seen that the bar 14 will be held firmly in position by members 14a and 14b. Bar 14 is constructed and arranged at its lower end to support a garment hanger 15. While said bar could be variously constructed, it is shown as having an arcuate slot 14c in one flat side which will conveniently receive the curved hook-like supporting portion 15a of the garment hanger 15. The cover 10a has secured, at its inner side, a flat plate spring 16, of bowed form, the

end portions of which are adapted to engage the topmost bag 13 to exert some pressure on the bags and hold them firmly in position with the lowermost bag engaging the flanges 10b.

In operation, the bags will be folded and disposed as shown in the drawing. When a suit, coat, or other garment is to be bagged, it is placed on the hanger 15 and the hanger then placed in the slot 14c, so that it occupies the position shown in Fig. 1. The operator now takes hold of the lowermost bag at the ends thereof, engaging the same through the slots 10c and pulls the bag downwardly. The bag readily moves downwardly through the opening between the flanges 10b and slides from said flanges, the bag being expanded as it is moved downwardly, since the folds therein will be successively retarded by the flanges 10b as indicated by dotted lines in Fig. 2. The movement is continued until the entire bag has been drawn from the container 10 and moved downwardly over the garment on the hanger 15. The bar 14, of course, extends through the axial passages 13c and the slots 13b in all of the bags; and the bottom of the bag withdrawn moves along bar 14 so that the closed end or bottom will eventually move over the hook-like supporting portion 15a of the hanger 15. The bottom of the bag will then rest on top of the garment on hanger 15 with the portion 15a projecting through the slot 13b. The garment is now nicely and completely covered by the bag which has been fully extended; and the covered garment and bag can be lifted from the bar 14 by taking hold of the supporting portion 15a. The bags will move or be fed downwardly in the container 10 by the pressure of spring 16. The cover 10a and member 14, together with spring 16, can be conveniently removed and a new supply of bags placed in the container.

While I have illustrated a bag container having a cover, it is obvious that this cover could be omitted and the upper end of the container left open, without impairing the efficiency of the apparatus or the method of its operation. Likewise, while I have shown a spring for the purpose of feeding the bags to the bottom of the container, a weight could be used to accomplish this purpose with equal effectiveness.

It is also important to note that the anchoring of the bar member 14 to the container 10 or another object prevents wobbling of the bar and assures lengthwise alignment of the bags with the hanger member 15. Of further importance is the fact that when the hook-like supporting portion 15a of the hanger 15 is fitted into the arcuate slot 14c, said hanger 15 will likewise be held rigidly in alignment with the bags as they are pulled downwardly and expanded over the hanger and garment being supported therefrom.

From the above description, it will be seen that I have provided a simple, convenient, and efficient method and apparatus for easily and quickly covering a suit or other garment or placing a bag thereover. The operation of withdraw-

ing the bag and moving it over the garment in expanded condition can be performed to very quickly cover a garment. The apparatus has been amply demonstrated in actual practice and found to be very successful and efficient.

While I have shown a preferred embodiment of my invention, it will, of course, be understood that the same is capable of modification without departure from the scope and spirit of the invention as defined in the following claims.

What I claim is:

1. A garment bagging apparatus comprising in combination a bag dispensing container substantially rectangular in horizontal section having an open end and a plurality of bags having their skirt portions folded in accordion pleated form and stacked therein in collapsed and longitudinally extensible condition with their open ends directed toward the open end of the container, said container having bag fold engaging means adjacent its dispensing end arranged to support the lowermost folded portion of the lowermost bag of the stack, a bar supported centrally by said container, one end of said bar extending beyond the dispensing end of said container and having means therein for removably receiving the supporting portion of a garment hanger, whereby the lowermost folded bag of the stack of bags may be drawn downwardly from said fold engaging means and gradually extended thereby over a garment on said hanger, said bar having means secured thereto and extending to and engaging opposite sides of said container for holding said bar in position.

2. A garment bagging apparatus comprising in combination a container for supporting a plurality of bags having their skirt portions transversely folded at spaced intervals in collapsed and longitudinally extensible form and in stacked arrangement with their open ends downwardly, said bags having aligned restricted central openings in their otherwise closed upper ends, said container having an open lower end with bag fold engaging and supporting flanges at opposite sides of the opening, a garment supporting bar adapted to extend vertically through said container and through the aligned openings in said bags and terminating in a garment hanger supporting means in spaced relation to the bottom of said container.

3. The structure defined in claim 2 in which said garment supporting bar is adapted to be removably supported adjacent its upper end from said container.

ARTHUR C. JOHNSTON.
